COIN CONTROLLED MECHANISM

Filed Sept. 22, 1932

UNITED STATES PATENT OFFICE

1,969,069

COIN CONTROLLED MECHANISM

John C. Gallaher, Nicholasville, and John P. Quiggins, Louisville, Ky.

Application September 22, 1932, Serial No. 634,426

2 Claims. (Cl. 194—101)

This invention relates to coin-controlled mechanism and is more particularly directed to a device for removing magnetic slugs from the coin chutes of such devices.

- 5 An object of the invention is the provision of a coin-controlled mechanism in which a chute is provided to receive the usual pieces of metal money for releasing certain elements of the coin-controlled mechanism to permit the dispensing of goods, a device being employed in connection with the chute for removing magnetic slugs when some party has attempted to operate the coin-controlled mechanism in an illegal manner.
- 15 A further object of the invention is the provision of a coin-controlled mechanism for dispensing goods in which a chute is employed to receive pieces of money with the chute having an opening at one side and a rotatable magnet adjacent the opening for withdrawing slugs and discharging the same from the chute, thereby preventing unauthorized operation of the dispensing device.

This invention will be best understood from a consideration of the following detailed description, in view of the accompanying drawing forming a part of the specification, nevertheless, it is to be understood that the invention is not confined to the disclosure, being susceptible of such changes and modifications which shall define no material departure from the salient features of the invention as expressed in the appended claims.

In the drawing:

- 35 Figure 1 is a view in elevation of the coin-controlled dispensing device partly in section showing the principles of the invention.

Figure 2 is a vertical section taken along the line 2—2 of Figure 1, and

- 40 Figure 3 is a horizontal section taken along the line 3—3 of Figure 1.

Referring more particularly to the drawing, 10 designates a housing provided with a coin slot 11 which provides an entrance to a coin chute 12 generally designated by the numeral 12. This coin chute has a vertical portion 13, a portion 14 which is inclined at an angle from the horizontal, and a second vertical portion 15 depending from the inner end of the portion 14. This last-mentioned portion is provided with an angular section 16 opening into a vertical chute 17 which deposits the coins into a receptacle 18 located within the housing 10.

A shaft 20 is mounted for rotation transversely of the housing and is provided with a

crank 21 for operating the shaft. A disc 22 is secured to the shaft and is directly rotated thereby. A second disc 23, spaced from the disc 22, is loose on the shaft.

A pair of rods 24 and 25 are pivotally connected on a crank pin 26 secured to the disc 22. The lower end of the rod 24 is pivotally connected with one arm of a bell crank lever 27. The other arm of the bell crank lever is pivotally connected at 28 with a slide 29 movable within a slot 30 formed in one wall of a dispensing chamber 31. The bell crank lever 27 is pivotally mounted at 32 on a bracket 33 secured to one face of the dispensing chamber 31.

The rod 25 is pivotally connected at 34 with a lever 35 which in turn is pivoted at 36 on a bracket 37 extending from the other face of the dispensing chamber 31. A plate 38 is pivotally connected at 39 with the lever 35 and is movable through a slot 40 formed in the wall of the dispensing chamber 31.

The pin 36 is rigidly secured to the lever 35 and also to an arm 41 which extends downwardly along one side of the dispensing chamber 31 and is provided with a lug 42 adapted to engage beneath the free end of a hinged closure 43.

A bar 44 is pivotally connected at 45 with the disc 23 and extends downwardly and passes through an opening 47 formed in a bracket 48. The passage 47 acts as a guide for the bar 44. A spring 49 secured between the bar 44 and the side wall of the dispensing chamber 31 is adapted to pull the bar 44 towards the adjacent side wall of the chamber 31.

The lower end of the bar 44 is provided with a cam member 50 having an inclined face. The upper end of the cam member is provided with a slot 51 adapted to receive an arm 52 secured rigidly to a shaft 53. The closure 43 is rigidly connected to the shaft 53 or to the arm 52, so that when the arm 52 is rocked, the closure will likewise be rocked.

A plunger 60 has a curved end 61 projecting into the portion 15 of the chute 13 and forms a seat to engage a coin, indicated in dotted lines and shown at 62. A rod 63 is pivotally mounted at 64 with the plunger 60 and has its free end 64 adapted to engage a finger 65 which is formed integrally with a stop or lug 66. The finger 65 and lug 66 form, together a bell crank lever which is mounted at 67 on the disc 23. A spring 68 has one end secured to a bar 69 and the other end is connected with the lug 66.

A link 70 is pivotally connected at 71 with the rod 63 while the other end of the link is piv-

110

totally connected at 71 with a finger 72 pivotally mounted at 73 on a bracket 74 depending from the chute 16.

A spring 75 is connected between the fixed bar 5 or plate 69 and the rod 63 for aiding in maintaining the free end 64 of the rod in an uppermost position.

A plunger bar 76 has bearings at 77 in the plate 69 and in the bottom of a casing 78 which 10 is suspended from the top of the housing 10. A spring 79 tends to maintain the plunger bar 76 in its uppermost position. The lower end of this bar is provided with a curved head 80 which is adapted to engage the coin 62 and force 15 it downwardly into the chute portions 15 and 16 and thus move the plunger 60 outwardly of the chute portion 15.

The bar 76 is provided with a lug 81 adapted to be engaged by a pawl 82 pivotally mounted 20 at 83 on the disc 22. A spring 84 maintains the pawl 82 in a predetermined position so that it will be engaged by the lug 81 when said lug moves to an upward position, as shown in Figure 1.

25 A pawl 85 has one end, as shown at 86, pivotally mounted on the disc 22. The other end, as shown at 87, is adapted to engage teeth 88 of a ratchet wheel 89 which is mounted for rotation and is secured to a shaft 90.

30 A magnet 91 has magnetic bars 92 and 93 secured to its ends and these bars are separated by insulating material 94. The magnet, as shown in Fig. 2, is secured to the shaft 90 so that when the ratchet wheel 89 is revolved the magnet will be rotated.

35 The portion 14 of the chute is provided with a slot 95 adjacent the magnetic plates 92-93 so that when a slug formed of magnetic material is dropped in through the chute 13 it will be picked up by the magnet and held until the magnet and the ratchet wheel 89 are revolved as will be presently described for removing the slug from the chute.

The operation of our device is as follows: A 40 loaf of bread or other article, shown at 100, is supported in the dispensing chamber 31 by the closure 43 which is held in place by the latch member 41 since the latch member and the closure plate 43 are located within the housing 10 it will be impossible for anyone to release the latch member 41 and open the closure 43 to obtain articles in the dispensing chamber. The articles 100 are deposited within a drawer (not shown) at the bottom of the housing. A coin 45 is deposited in the slot 11 and passes downwardly through the chute and rests upon the seat 61 of the plunger 60. A handle 21 is then operated in the direction indicated by the arrow in Fig. 1. Since the pawl 82 is in engagement with the lug 81, said pawl will force the plunger bar 76 downwardly so that the plunger foot 80 will engage the coin 62 and force it past the inner projecting end of the plunger 60. As 50 the coin is forced past the inner end of the plunger 60 the plunger is moved outwardly, thereby exerting a pull on the rod 63, thus moving the rod in the direction indicated by the arrow so that the free end 64 of the rod is released from the finger 65. The spring 68 then 55 draws the lug 66 upwardly so that a pin 66^a on the lug will be engaged by a lug or tooth 91^a

formed on the disc 22. Continued rotation of the disc through the crank or handle 21 will cause the disc 22 to be moved, thereby moving the rods 24 and 25 in the directions indicated by the arrow so that the plates 29 and 38 will be moved inwardly of the slots and engage the bottom of the next article and retain it in the uppermost position above the article 100 in the dispensing chamber 31. When the disc 23 is revolved the rod 44 is also moved upwardly in the direction indicated by the arrow so that the lever 52 will be rocked, moving the cover 43 downwardly in the direction indicated by the arrow. However, a movement of the rods 24 and 25 being in advance of the movement of the rod 44, the lever 35 will be rocked when the plate 38 is shifted inwardly and the latch 41 will be released before the rod 44 is operated to rock the closure 43.

50 At the time that the bar 63 is shifted the link 70 will also be moved downwardly, thereby releasing the coin, as shown at 102, which is then deposited within the till 18.

If on the other hand, a magnetic slug is dropped into the slot 11 it will roll downwardly into the chute 13 until it comes opposite the magnet 91. This magnet will attract the slug to the same so that when the ratchet wheel 89 is revolved by the pawl 85, the coin will be moved outwardly through the slot 95 until it engages 105 the top 103 of the chute portion 14, whence the slug will be forced away from the magnet.

110 It will be seen by this construction that when the proper coins are placed within the slot 11 the device may be operated for dispensing bread or any other article. On the other hand when magnetic slugs are placed in the device the magnet will remove them when the handle 21 is operated.

We claim:

1. In a coin-controlled mechanism for a dispensing apparatus; a chute having an opening, means for removing from the chute slugs formed of magnetic material and comprising a magnetic member mounted for rotation at the opening for attracting the slugs from the chute, a shaft connected to the magnetic member, a ratchet wheel secured to the shaft, a disc operatively connected with the dispensing apparatus; a pawl engageable with the ratchet wheel and pivotally connected with the disc, and means for rotating the disc.

120 2. In a coin-controlled mechanism, a coin chute having a portion cut away for the removal of slugs formed of magnetic material and moving through said chute, a magnet having a member filling the cut away portion of the chute to prevent coins from falling from the chute at this point but capable of attracting and holding slugs formed of magnetic materials, means for rotating the magnet and connected member so when a slug is held by the magnet, the slug will be moved out of the chute, a portion of the top of the chute being cut away to permit removal of the slug, a portion of the top adjacent the cut away portion of the top being engageable with the slug and forcing the slug off the magnet.

JOHN C. GALLAHER.
